UNITED STATES PATENT OFFICE.

ANTHONY RUTGERS NEILSON, OF ELIZABETH, NEW JERSEY, ASSIGNOR OF ONE-HALF
TO NATIONAL CITY BANK, OF NEW YORK, N. Y., A CORPORATION.

MONEY-COUNTER'S DESK.

1,368,827.

Specification of Letters Patent. Patented Feb. 15, 1921.

Application filed April 6, 1920. Serial No. 371,763.

To all whom it may concern:

Be it known that I, ANTHONY RUTGERS NEILSON, a citizen of the United States, residing in Elizabeth, in the county of Union 5 and State of New Jersey, have invented certain new and useful Improvements in Money-Counters' Desks, of which the following is a specification, taken in connection with the accompanying drawings.

10 My invention relates to a bank desk and more particularly to a money counter's desk. My invention further relates to such a money counter's desk in which the responsibility, for any given sum of money to be counted, 15 is individualized. The money can be locked or secured on said desk, but is always visible and open to inspection, the desk not interfering with the free-ventilation of the money counter's cage in which the desks are usually 20 placed. It further relates to such a desk in which not only the money on each desk is visible at all times, but also the work of an employee can be seen by the chief of the money counting division, as well as by the 25 other workers, so that the money counters act as a check on each other.

It further relates to such a money counter's desk in which the contents of the desk, as well as the work of the employee, can be 30 seen at all times by a detective located at some point of observation, as for example a balcony or window overlooking the money counter's cage.

My invention further relates to a money 35 counter's desk having a removable hood and cover, which can, in an emergency be taken from the top of one desk or table and secured to another desk or table.

My invention further relates to certain 40 combinations and articles of manufacture and details of construction all of which will be more fully hereinafter described and pointed out in the claims.

In the figures in which I have shown one 45 embodiment of my invention the same reference numerals refer to similar parts in the several figures.

Figure 1 is a side elevation of two of my money counters' desks, one being shown 50 open and the other closed and locked;

Fig. 2 is a vertical section through the open money counter's desk shown in Fig. 1;

Fig. 3 is a vertical section, on an enlarged scale, on the line 3—3 of Fig. 2;

5 Fig. 4 is a horizontal section on the line

4—4 of Fig. 2, looking down in the direction of the arrows;

Fig. 5 is a detail vertical section on an enlarged scale;

Fig. 6 is a vertical section on an enlarged 60 scale on line 6—6 of Fig. 2, looking in the direction of the arrows;

Fig. 7 is a plan view of a money counter's cage showing a plurality of my money counting desks, some arranged back to back, and 65 some arranged around the cage.

In banks, and particularly large banks, the duty of counting large sums of money passing through the bank is a most necessary and exacting part of the daily routine. 70 In a large bank the money received from each teller has to be checked by the money counters before it is placed in the safe for the night and the account of that teller properly checked and passed as being correct. 75 In such large banks money is being, from time to time through the day, taken from and returned to the vault. Money from out of town correspondents, including foreign correspondents, of course also has to be 80 counted and checked.

This duty of counting the money is done by a corps of employees known as money counters whose work is practically continuous throughout the banking hours, and also 85 after such hours, as it is necessary to check up the money returned from each teller, prior to placing it within the safe.

Necessarily these money counters must be 90 persons of scrupulous honesty and integrity. They usually work under pressure and great strain due to the great responsibility of their duties. They also have to watch for counterfeit money.

It is customary, from time to time, during 95 the day for the chief of such a division of the bank to receipt for hundreds of thousands of dollars, his receipt being subject to actually counting the money in his department. In a large bank it is impossible 100 for the chief of such a division to do all of the counting of the money himself; in fact his time is very largely taken up superintending and directing his staff of money counters.

The usual practice in such large banks is 105 for the chief of the division, after giving his own receipt for a certain amount of money, to turn this entire amount over to one of his assistants, he charging the par- 110

ticular assistant with the sum for which he has given his own receipt or acknowledgment. Of course, as previously stated, the receipt of the chief of the division is subject to the amount as found on actual counting of the money in his department.

The assistant money counter is then responsible to the chief of the division for this entire amount until he counts it and returns it as being correct, or incorrect, when the discrepancy is found and the amount made to correspond with the actual sum of money turned into the counting division.

This throws great responsibility upon not only the chief of the division but also upon his assistants.

Even with the utmost care in selecting the assistants for this important work occasionally a dishonest one can not withstand the temptation to peculate, and even in some cases to take comparatively large sums.

In a corps where there are many money counters, one of whom is dishonest, suspicion is necessarily shared by all the employees. If the peculations continue the bank loses more or less money and the morale of the counting division is seriously undermined as they are at all times under great strain from the very nature of their most exacting labors.

In a large bank it is not at all unusual for many of the money counters to have at one time in their charge between five and six hundred thousand dollars (\$500,000 to \$600,000) in currency and often more, for which they are personally responsible until it is all counted, checked and returned to the chief of the division, who then, on his own list makes the proper notation relieving this employee of the responsibility for this amount of money. Counting such amounts of money is not only arduous labor but takes time. If the lunch hour occurs in the midst of counting a certain batch of money, for which the employee has been charged, he runs a risk in leaving it on his desk, as he is personally responsible for this entire amount until it is returned to the chief of the division and he has been released from further responsibility.

Banking floor space is so valuable and it being necessary to have the money counters near the tellers and the vault, so as to run the least risk of robbery, that in large banks the money counters are put in out of the way locations, where the light and ventilation is usually the poorest.

By my invention each money counter has his own money counting desk which is entirely under his own control. If he has to leave his work temporarily for any cause, he can lock his desk, so that no other employee in the money counting division can tamper with it. Further the contents of his desk, open or closed, will always be visi-

ble to the chief of the division as well as to other employees of that division. The chief of the division may also have a master key in case it becomes necessary for him to reach the contents of the desk in the temporary absence of the employee.

In my improved money counter's desk not only is all the money on the different desks visible at all times to the chief of the division and to other employees who themselves act as a check on each other, but there is no obstruction to the free ventilation of the money counter's cage or compartment which is a most important item for the ventilation of these money counters' cages or compartments, is never good, due to their being crowded into the least desirable space on the banking floor and usually away from all windows.

By my invention the work of each employee as well as all the money on his desk can be watched at all times by detectives in any commanding and concealed location as for example from a balcony or window overlooking the money counter's cage.

In the particular embodiment of my invention shown in the drawings, 1 is a money counter's desk having a top 2 and a hood 3. This hood is formed of wire and has a back 4, sides 5, 5 and a dome 6. Mounted to slide within the dome is a movable cover 7, also of strong open work, preferably wire. Any suitable means may be employed to counter-balance the weight of the cover. Preferably I attach the strap 8 to the cover at the other end of the strap being connected to a coiled spring device 10 of any suitable construction which is put under tension when the cover 7 is pulled down to close the money counter's desk, as shown on the right of Fig. 1. Two of these coiled spring devices 10 are preferably employed for each cover 7. It is to be noted in Fig. 1, that the top 2 of the desk is provided with two hoods and two covers, so that it is in effect two counting desks, each one being assigned to a different money counter.

While at work counting the money 11, the cover 7 is pushed up by means of the handles 12, 12 and assumes the position shown at the left of Fig. 1. If the operator has to leave his work temporarily for any purpose he pulls down the cover 7, as shown at the right of Fig. 1 and locks it by the lock 13, so that the contents of that money counter's desk can not be tampered with by any other employee in the money counters' cage 14, Fig. 7. The contents of that desk, however, is at all times visible to the other employees, whether the desk be opened or closed, and particularly to the chief of the division whom I have designated as 15. Preferably he, and he only, has a master key which can open any one of the money counters' desks, should it be necessary to reach the contents 130

in the temporary absence of the money counter.

For the reasons previously given the ventilation of the money counters' cage 14, in which numerous employees work, is at the best very poor. Usually these employees have to work under artificial light. I have shown in my drawings an electric light 16 mounted in a reflector 17, there being one reflector 17 with several electric lights 16 for each desk.

By my invention the discomfort due to the heat of these electric lights and the crowded condition under which the employees in the money counters' cage 14 have to labor, is reduced to the minimum, for the reason that by my invention my money counter's desk does not interfere with the free ventilation of the money counters' cage 14 and the free ventilation of each desk.

In practice the chief of the money counting division may occupy any position in the money counting cage 14. As a matter of convenience he may, though not necessarily, assume the position designated 15 near the locked door 18 of the cage 14 so that he can have under his general observation the work of the other employees 19 in the cage without leaving his own desk. From time to time, of course, he may walk around to more closely inspect the different workers in the cage but at all times he can see the contents of each money counter's desk, whether the money counter is at work or whether his desk is closed and locked, as some of them are shown in Fig. 7.

By my invention the hood 3 with its dome 6 may be removed, if desired and placed on a new top 2 by unscrewing the screws 20 holding the flange 21 to the top. Within each money counter's desk I preferably,

though not necessarily, place a glass shelf 22. I provide the sides 5, 5 with a curved angle iron 23, the flange 24 acting as a guide for the U-shaped member 25 carried 45 by the cover 7, there being different U-shaped members 25 on each side of the cover 7.

Having thus described this invention in connection with an illustrative embodiment 50 thereof, to the details of which I do not desire to be limited, what is claimed as new and what is desired to secure by Letters Patent is set forth in the appended claims.

What I claim is:—

55

1. A new article of manufacture comprising a money counter's desk provided with a top, an open work hood mounted on the top, a movable open work cover, and means to lock the cover to the top of the 60 desk so that the money will be visible from all points and open to inspection whether the desk is opened or closed but cannot be tampered with by other employees, the hood and cover permitting free ventilation of the 65 desk.

2. A new article of manufacture comprising a money counter's desk provided with a top, a removable open work hood mounted on the top, a movable open work 70 cover carried by the removable hood, and means to lock the cover to the top of the desk so that the money will be visible from all points and open to inspection whether the desk is opened or closed but cannot be 75 tampered with by other employees, the hood and cover permitting free ventilation of the desk.
